UNITED STATES PATENT OFFICE.

HERBERT V. THADEN, OF DETROIT, MICHIGAN, ASSIGNOR TO AIRCRAFT DEVELOPMENT CORPORATION, OF DETROIT, MICHIGAN, A CORPORATION OF MICHIGAN.

AIRSHIP MOORING.

Application filed September 2, 1925, Serial No. 53,981. Renewed October 24, 1928.

The subject-matter hereof relates to inventions in methods of mooring airships and apparatus for mooring of airships. Among the particular objects are to provide better facilities for the practical operation of bringing the ship's nose to a secured relation to an elevated anchorage such as a tower or mast and then to permit the swaying of the ship completely around the mast, also when it is desired, to move the mooring connection down the mast with ease while constantly moored securely, for the purpose of allowing the airship to assume a lower position even to the extent of berthing the ship in contact with the ground.

My method and type in general are such as set forth in my United States application Serial No. 687,689, and this my present application involves further developments, modifications and improvements for my type of mooring tower which provides for drawing a ship to an elevated point and either holding it there, or at will providing for the lowering of the ship.

Among the particular features, I provide a coupling means which after securing the ship may be readily shifted bodily down the mast without any change of the coupling connections with the ship's nose, also providing a coupling which permits the ship when moored at the top to swing completely around the mast while the mooring carriage remains in a fixed position, also features of such a mooring carriage which accommodate without improper strains the various movements of the ship such as rolling or pitching or yawing, also to absorb the shock and yield to shock of a ship when stopped as it reaches the mast. Other features provide for more convenient or for more economical tower structure, and for better resistance to winds, as also to increase the facilities of operation by the landing crew, as well as to assure greater safety and certainty in the mooring operations, and in particular to facilitate the coupling of the ship to the mast by easy adjustment of the coupling member on the mast into the proper position.

While many variations may be made in the apparatus, and modifications in the method of mooring, particular constructions of the apparatus with some modifications are illustrated in the accompanying drawings, in which:

Fig. I is a side view in perspective, showing a mooring tower containing features of

the invention and with the forward end of an airship adjacent in positions of mooring to the tower or mast.

Fig. II is a side elevation of the mooring mast top turret and the top mooring "horn".

Fig. III is a plan view of the mooring horn and shock-absorbing linkage on the tower top turret, on a slightly larger scale than in Fig. II.

Fig. IV is a view of the securing-carriage for engagement with the ship's nose coupling, as shown attached to the vertical guide shown in section, being a top view when said carriage is in position of horizontal axis.

Fig. V is a fragmentary vertical section on the line 5—5 of Fig. IV.

Fig. VI is a vertical section of the carriage shown in Fig. IV.

Fig. VII is an end view of said carriage, on a smaller scale than Fig. IV, as viewed from the end receiving the cable coupling.

Fig. VIII is a fragmentary view of the connection of the vertical guide and its ring-girder carriage, ring-girder and adjacent tower member.

Fig. IX is an elevation showing a modified arrangement of attachment of the vertical guide to the ring-girder.

Fig. X is a side elevation of a modified form of tower or mast on a scale generally similar to Fig. I.

Fig. XI is a vertical section, fragmentary, showing the base connection of the modified tower, Fig. X, on a larger scale.

Fig. XII is a side elevation of a modified form of tower or mast.

Fig. XIII is a fragmentary view of the top carriage retaining rail and horn in the tower shown in Fig. XII.

Fig. XIV is a typical cross-section of the main length of the tower, Fig. XII.

Fig. XV is a cross-section on a slightly smaller scale of a modified section of a tower on stream lines.

The drawings show in the first place an embodiment which comprises the tower A, having a vertical guide B which merges into a top portion or horn C supported on a turret D and having shock-absorbing linkage E—E', a movable belaying block or coupling carriage F adapted to receive a mooring cone on a mooring cable H and to be secured by cone locking pins J, while the cone is connected with the ship's nose by spindle K and spindle pin L.

The main haul-down cable L cooperates with an upward carriage control-cable L' for manipulating the carriage. A horn pivot H permits movement of the horn in conjunction with the shock-absorbing linkage E—E' all on the turret, and suitable means as a motor N, through gearing and shaft, may control the rotation of the base of the turret D on top of the otherwise stationary mast, while shaft O or other suitable connections may be coordinated with the rotarily-swinging vertical guide B to control the motion of the guide in parallelism from top to bottom.

The inner cone P is supported on bearings 15 to revolve on its axis within the outer cone Q, and may be locked against rotation in the outer cone by cone pin R. The outer cone Q is adapted to swing on top and bottom cone pivots S in the frame formed by cross-beams T—T and arch plates T'—T' which laterally carry pivoted guide blocks U and straps U', engaging the rails b of the vertical guide B, so that the entire carriage can slide from bottom to top of the guide and 25 also onto the horn to positions above the turret even to the axis of the mast. Guide B supported from the mast rings V, by ring-carriages W permits the swing of the guide B around the mast in unison with the turning 30 of the turret D around the top.

In the modified form shown in Figs. X and XI, the tower A' is rotatable as a whole around the foundation X and has the vertical guide B' along an element of the tower rigidly secured thereto, so that the tower and element rotate about the axis, instead of having a separately rotatable mast-head turret. This modification preferably is a sheet steel structure Z with ample base braces Z' which 35 engage, as by bearing Z'', with a plurality of shafts Y' having suitable rollers Y'' on their ends and supported so as to rotate from a hub Y. The rollers may alternately engage top and bottom rails X' solidly supported by the base foundation X. This affords means 40 for housing stationary power apparatus, and supplies or equipment to meet the best conditions of operation and soundly anchoring the structure.

50 The details of the essential parts hereinbefore recited will now be explained in the embodiment shown. The tower has a well braced base by legs 1—1—1 and internal braces throughout the upper part without outside 55 guys. The top base 2, has inverted rail 3 and upright rail 4 which engage, respectively, a plurality of rollers 3' and 4' on the turret top comprising a horizontal structure with platform, which may accommodate housing 60 and various apparatus. From one side of this turret platform the vertical guide rail B merges by a pivotal connection M into a curved top end called a horn reaching to a position substantially horizontal in the axis 65 of the mast. Near its apex suitable connec-

tions attach a bumper cylinder E, preferably in the plane of the horn but on the opposite side from its articulated connection with the guide B, to accommodate compression or tension. Lateral bumper cylinders E' absorb any lateral strains transmitted to the top of the horn. Centrally of the turret is a pipe 5, which provides guide and protection for the handling cables. The haul-in cable H passes over a sheave 6 deflecting it substantially in the axis of the mast, and where it enters the tube 5 a belaying or compressor clamp 7 provides for making-fast when the ship's nose is chock-a-block with the coupling carriage, to permit proper manipulation of the line preparatory to lowering the ship or to handle the cable preliminary to releasing the ship. The hand-winches 8 provides for initially pulling down the carriage F from the upper part of the horn and may be interposed in the haul-down line L which otherwise extends to a lower portion of the mast to serve for the carriage control throughout its range of movement on vertical guide B. The motor N drives the shaft and through 90 gearing engaging the fixed rack 9, provides for turning the turret to any position desired during the approach of the ship, as well as easing the swing of the vertical guide in response to the shifting position of the ship 95 by-the-wind. The carriage F coupled to the ship, when in a position on the horn or at its top has lateral strains absorbed by the supports and linkage, thereby relieving sudden strains from being fully transmitted to 100 the mast proper.

The cone carriage having the frame with cross-straps T, is supported for lateral angular pivoting throughout sixty degrees without interference with the vertical guide B, while roller bearings and thrust bearings 10, permit the inner cone B to swivel on its axis until the ship has settled to a ground mooring or it is otherwise desired to stop the cone from rotation, and then locking pin R is 105 thrown in by hand-lever 10'. The up-haul cable L' is attached to a link 11, and the down-haul cable to eye 12, while a supplementary haul-up line L'' operated by hand-winches 13, may be connected and quickly disconnected by an over size link engaging a spring-held pin 14. The nose cone locking pins J—J are spring-pressed for engagement with suitable hand grips 15 for releasing the pins which when drawn out provide 110 for keys 16 engaging holes 17 to hold the pins in released position.

The attachment of the vertical guide B to the horizontal rings V is shown in smaller scale in Fig. VIII wherein a fixed structural member 18 of the tower holds the rail V which is engaged by beveled rollers 19 carried in bearings on a bracket 20 fastened to the inside vertical members 21 of the guide B. As the vertical guide connection to the 115

- rings may require adjustment as in the case of 100 or 200 foot masts, it may be desirable to provide for the mounting of the carriage W, as shown in Fig. IX wherein the bearings of the rollers are carried on a bracket 22 engaging a vertical rod 23 carried on the vertical guide B in such manner that the vertical adjustment is provided, and in addition a slight swiveling of the vertical guide.
- 10 It may under certain conditions or positions of carriage be desired to permit the inner cone to rotate on its axis, but to lock the outer cone to prevent yawing on the pins S, and for that purpose I may use locking pins 24—24 passing through the carriage strap U preferably the upper one, and registering each with a recess in a substantial part of the outside of the outer cone, which pins can be thrown in and released by lever 25 actuated by handle 26, with a toggle connection to lever 25^a to simultaneously actuate the companion pin, there being suitable supports, as shown, for each lever. The registering of these pins 24 is such that when locked 25 the outer cone is held in a central position, namely, with its axis normal to the plane of the carriage frame. In that position the coupling when at the extreme top of the horn C, as shown in Fig. II, will be in a position with 30 the axis of the cone vertical and substantially coincident with the axis of the mast and held in such position with the inner cone free, will permit it in connection with the ship's nose to revolve completely around the mast without 35 tilting of the cones due to any lateral strain when the ship has swung to a position out of the vertical plane of the horn.
- In the modified form of tower shown in Fig. XII with its detailed views, the tower 40 A is supported on thrust and lateral bearings 27 near its bottom to carry the load, while bearings 28 at a substantial elevation above the base bearings afford lateral support, as in the bracing 29 which may be a housing 45 providing for the cable-winch 30 and a floor 31 for crew quarters, and floor 32 for tower rotating engine. Within the tower an elevator 33 is accommodated without interference with the centre cable tube 34 guiding and 50 protecting cables and electric conductors to the extent needed for the mast-head operations, with preferably a box girder 35 on one side securely supporting the vertical guide rails 36 on the outside of that side of the tower. While the elevator would run to a 55 position below the top of the main section of the tower, a platform there provides access to stairs 38 leading to the mast top platform on which the guide rail 36 is supported in a position inclined toward the axis of the tower and joins with an articulated section 39 connected by pin 40 corresponding to the horn in 60 the previous forms described but modified in certain features. These modifications involve the provision of a retaining guide rail 65
- 41 near the upper part of the horn apex down to about fifty degrees, which may be a spiral generated from the sheave over which the main cable is reeved, while an inner mooring carriage rail 42 corresponding to the lower portion 36, permits the engagement of the mooring carriage 43 both on the outer guide rail and the inner guide rail during the movement from the top and through an arc from twenty to fifty degrees. Thus when the carriage is close to and at the apex of the cone it is supported by the outer guide rail engaging the lateral guides 44 on the carriage, which prevent the carriage flower pot or cone from lateral pivoting and assure the swiveling of the ship's cone coupling on the axis of the carriage. As the carriage 43 is moved to the side and down, the inner legs 45 engage the inner rail 42 and after passing to a near vertical position of the guide rail, the coupling carriage clears the outer rail and is held entirely by the inner rail lugs 45 which connect with the carriage by members 46 which may be arranged to permit lateral pivoting on such vertical connection to accommodate yawing of the ship in case the power does not respond in rotation of the mast with the shifting of the ship by-the-wind while being lowered or when moored to the ground. Such connection in any event prevents the coupling cone from swiveling when the mooring carriage is shifted down the mast and assures a more extended engagement with the guide rail on the side of the mast permitting freer motion and also offering conveniences for the reeving and handling of pull-up and pull-down cables by which the mooring carriage 43 is controlled.
- In the cross-section shown in Fig. XV the central cable standpipe 34 is the centre of rotation and the leeside of the tower with vertical guide rails 36 being the side of the tower to which the ship is secured, offer the provision of an extended nose on the opposite side of the tower from top to bottom, such as the projecting wind-deflecting sides 47—47 extending laterally past the middle and to projections 48—48 forming lateral walls on the leeside of the tower between which the ship's nose connection is housed. Such stream line section of tower provides for elevator 33', the weight of which with its cables are thus offset from the centre of the tower to a greater extent on the windward or tension side of the tower elements, than is possible with a circular section tower giving in certain cases advantages for the economic resistance of the wind strains. While the stream line section of the tower to an extent deflects the wind in the vicinity of the ship's nose for the purpose of gaining any possible reduction in mast strain when the ship is moored.
- The practice of my invention will now be understood as follows: An air ship or dirigible, as indicated in part in Figs. I and

X, is warped in by means including a nose cable attached to the nose spindle and having a coupling cone. If winds lift during the approach to the mast the top turret holds the carriage cone or "flower pot" with its axis vertical and in the axis of the mast, accommodating the ship's swing. When coupled to the carriage by hauling in the nose cable snug and locking the cone to the carriage flower pot, the bearings on this flower pot permit free rotation and swing throughout the entire 360 degrees. If the ship's nose spindle does not project sufficiently to let the ship clear the horn, the carriage may be shifted from the top position to, say, thirty degrees down the bend of the horn where the ship's swing is accommodated by turning the turret and horn. The pitching of the ship and other variations in strain are cushioned by the bumper linkage E—E'. The rolling of the ship is accommodated by the inner cone P turning in the outer cone Q. As the ship by manipulation of ballast or pull-down ropes is gradually lowered, the carriage F slides or is pulled down the horn, passes from the horn C to the main vertical guide B and down to the position of the nose when the ship's landing gear reaches the ground. When moored, any change of direction of wind is accommodated by the entire shifting of the vertical guide B around the tower, or in the case of the rotating tower, the guide B' and tower rotate by-the-wind. Throughout, slight variations of the ship's shifting by-the-wind while attached to the carriage, are accommodated by the vertical pivots S pending the following movement of the guide rail to a position of direct horizontal pull with the steadyng of the strain of the ship's nose. When the nose cable is pulled down to engagement of the cone with the carriage flower pot, the pins J automatically lock the same in position throwing the strain upon the carriage and horn and then the vertical guide, depending upon position of elevation, and then tension on the haul-in cable can be released permitting the carriage to move freely down the horn and the guide. The haul-down and haul-up cables attached to the carriage reeved to near the top of the horn, and as shown in Fig. II may be turned down and passed through the axis of the tower or any suitable connections such as a conduit or central pipe, facilitating their manipulation from the base of the tower or at any suitable location in the tower. The haul-in cable likewise can be run down in an axial position, preferably in a conduit or standpipe, to be operated by power at the base. Belaying clamps on turret or associated with rigid central structure of the mast can hold, as shown, the haul-in cable and take up the strain so as to permit the hand-releasing of pins J—J when it is desired to clear the cone and free the ship from the mast. In

the case of the modifications in Figs. XIII and XIII, the horn is varied and the coupling carriage altered. The main vertical rails are engaged by extensions on the base of the carriage until the carriage passes to a position near the top of the horn where the main rail section ends after the sides of the carriage or flower pot ride onto another pair of rails used only for the support of the carriage when at or near the apex. 75

Broadly my method consists of securing an airship to the top of a tower or other sufficiently elevated point where normal diving or dropping by the tail will not endanger collision with the ground, and thereafter 80 without change of coupling moving the point of attachment down the tower and warping the ship down to the ground so that points of attachment on the ears or any other desired points on the belly or sides of the ship can be 85 made fast to ground gear adapted to resist lift as well as carry the load of the ship for variations of trim.

To effect this method, the apparatus involved in my invention includes preferably a 90 tower without outside guys and having a vertical guide extending from the lowest desired position of a ship's nose when moored to the ground, to near the top of the tower or mast and there merging into a horn curving inward 95 to the apex of the mast where it becomes substantially horizontal, but having a pivoted connection between horn and vertical guide on a turret top or main section of the mast. Thus the entire top can revolve with the horn, 100 and carries a limited amount of manipulating gear and a small mast landing-crew. Suitable connections provide for turning the turret at will, and simultaneously easing the 105 swing of the entire vertical guide rail or positively controlling its swing around the mast, or turning a main section of the mast around its axis.

In cases where I find it constructively and operatively practical to extend the turret portion downward to lowest level to which the nose may be attached when the ship is grounded, I secure the vertical rail fixed to the mast side and preferably enclose the entire structure forming a sheet metal tower structure, 110 with widely spread base bearings to carry the load and the strains due to the wind pressure and tug of the ship. This is preferably with the top section of the guide rail formed as a 115 horn with cushioning means to absorb sudden strains from being wholly transmitted to the entire structure. In any event, the horn has linkage which assures its normal position preferably with the top of the horn substantially in the axis and at the apex of the mast, while buffer cylinders or like shock-absorbers 120 permit suitable yield of the horn in its plane, and absorb any lateral jerking strains at the top of the horn.

By such constructions the severe landing 125

strains are accommodated at the top of the mast with great facility of control and manipulation of the nose cable, or other cables from the bow of the ship. The apparatus 5 also permits leading main or other cables through the axis of the top turret, or rotatable section, to stationary winches at the base or lower portions, thereby reducing to a minimum the apparatus required at the top of the 10 mast.

The mooring of a ship will thus proceed by the usual connecting of the mast mooring line to the ship's bow line, with a suitable cone coupling member, hauling in the bow cable 15 until the cone reaches the mast, and there the cone is pulled directly into a flower pot which forms the inner portion of a carriage waiting at about thirty to forty degrees down the bend of a horn, and adapted to ride on the horn 20 and from the horn to the vertical guide. The yawing of the ship, as well as the pitching and rolling, are all accommodated by the particular construction of the carriage providing for 25 rotating of the cone in the carriage, and lateral swiveling in a horizontal direction of the cones in the frame section of the carriage, and being furthermore connected with the rail members of the horn in a way to permit 30 easy sliding of the carriage even to the curve of the horn as by swiveling guide blocks and free fitting guide block straps holding the carriage securely to the rails. To meet all 35 the exacting conditions of manipulation, light hand-winches serve for raising the coupling carriage up the curved horn section and to 40 pull it down after the ship has been coupled-up until the carriage reaches the lower position of the horn where the main pull-down cable attached to the bottom of the carriage 45 leads through the vertical rail structure in a suitable manner permitting its manipulation from below or through a return-bight back to the turret and down the central cable conduit. The pull-up cable is readily attached 50 to the top of the carriage and reeved over the sheave above the top platform and down the cable pipe for winch control at the base. As 55 the coupling carriage providing for all the advantageous features is still a short apparatus, it readily permits the mooring cable to pass through and clear the carriage close to the horn rail so that it is readily reeved over a top sheave, while still permitting all 60 desired freedom of motion of the carriage at 55 the top of landing. Preferably the topmost section of the horn forms substantially the arc of a circle or spiral generated by the cable in contact with the sheave, thus permitting 65 free movement of the carriage on the top portion of the horn throughout a range, such as for thirty to forty degrees, as the preferred carriage position for landing operation. The main length of cable leading from the turret down may then be belayed by compressor or 70 clamp at top deck, and a coupling released, 75

thereby freeing the cone from the cable after it has been locked in the flower pot or carriage cone. At this point the carriage is free to be run down the horn with the gradual grounding of the ship, and may follow the 70 ship's nose or the carriage may be eased along by the lowering or raising lines, and in any event is always under complete control. When starting flight the carriage may be readily hauled up, thereby raising the ship's 75 nose simultaneously with suitable adjustment of trim, and when reaching the upper portion of the horn any desired or quick departure is accomplished by instant release by men stationed at the top of the horn pulling the 80 readily accessible locking pins which clear the carriage cone and free the ship's nose. A slow release is equally practical by coupling the top end of the mast cable with a short length extending through the hole in the carriage base attached to the cone, and then controlling the paying-out of the cable as desired.

It will be seen that even though the rotating means of vertical guide or turret should be jammed, my carriage when at the top of the horn permits the ship to swing by-the-wind the entire 360 degrees around the tower. While the yawing of the carriage cones may be desirable when the carriage is down from the top of the horn, when at the extreme top 90 the axis of the cones should be vertical and the locking pins or straightening-up mechanism is then thrown in to hold the outer cone 95 stationary and prevent its pivoting in the carriage, while still permitting the inner cone 100 to swivel entirely around its axis and also supporting the coupling cone in a position so that the pin connection with the ship's nose is horizontal thereby permitting the ship to 105 pitch. However, when the carriage is moved down reaching the vicinity of a forty-five degree position it becomes necessary to make sure that the pin linking cone with the ship's 110 nose remains horizontal to accommodate any 115 pitching, and at the proper time therefore the locking pin R is thrown in holding the flower pot against rotation on its axis, due provision having been made at the time of 120 coupling the ship's nose to provide for the locking of cone in the flower pot in a position 125 whereby the spindle pin is horizontal when the flower pot is locked by the pin R.

It will be noted that in the practical handling of a ship when landing, instead of the bow of the ship "hunting", the "finding" is easier as the carriage can be readily adjusted on the horn and the turret can be readily turned, so that a union of the ship's spindle cone with the flower pot or carriage cone is greatly facilitated.

Many variations may be made, particularly in structural detail from that shown and particularly described herein, and features of the invention may be used in other combinations,

and the masts may of course be of varying heights and variously tapered and formed with bases to suit any particular conditions, but what I claim and desire to secure by Letters Patent is:

1. A mooring mast for airships including a mobile coupling carriage adapted to receive and hold a ship's mooring coupling at the top of the mast and permit the ship to swing around the mast axis without movement of the mast bracing, strain-resisting means interconnecting the mast and said mobile carriage while the ship is moored at the extreme elevated position on the mast and without change of coupling holding the carriage at all positions of declination and from a position approximating the axis of the mast and when moved down the mast side to position of ship's nose when the ship is moored to the ground.
2. A motor tower for airships as set forth in claim 1, having a mobile mooring coupling carriage slideable up and down the mast embodying engaging means permitting rotation of part of the carriage to allow the ship's coupling and engaging member to rotate together.
3. A mooring tower for airships as set forth in claim 1, having pivotal means supporting a part of the mobile coupling carriage, whereby pivotal oscillation of part of the carriage is permitted on a substantially vertical axis in position below the top of the mast.
4. A mooring tower for airships as set forth in claim 1, having a mobile coupling carriage embodying means for locking the ship's cable cone automatically in fixed engagement with a part of the coupling carriage.
5. A mooring tower for airships as set forth in claim 1, having voluntary locking means associated with a part of the coupling carriage preventing the rotation of the ship's coupling engaging member.
6. A mooring tower for airships as set forth in claim 1, having means for locking the cable coupling engaging member against oscillation in the carriage from its substantially vertical support when at the top of the mast.
7. Mooring apparatus for airships comprising a mobile carriage for engaging a ship's mooring cable nose connection, a lateral strain-resisting guide holding said carriage in positions from horizontal to vertical and permitting free riding of said carriage while permanently connected with the ship's nose from a position substantially vertical with respect to the carriage coupling axis to near horizontal, articulated means supporting the guide for said carriage, and shock-absorbing connections to permit shock displacing movement of the upper part of said guide.
8. Mooring apparatus for airships comprising a deflected guide extending from a near vertical at the side to a horizontal posi-

tion at an uppermost part of the guide, a mobile mooring carriage engaging said guide with cooperating brace members resisting lateral tug of the ship at the uppermost part of the guide and horizontal wind strain resisting means throughout the near vertical portion of the guide to resist ship's tug in a radial direction from the axis of the mooring apparatus.

9. In a mooring apparatus for airships, a mobile mooring coupling carriage, cooperating guide rails for said carriage extending from a near vertical to a horizontal uppermost position, shock-yielding members associated with the upper part of said guide and an articulated lower end of said guide cooperating with a non-articulated downward extension registering guide, whereby the coupling carriage may be manipulated throughout the articulated section and down the remainder of the guide without uncoupling of the ship connection.

10. Mooring apparatus for airships comprising a mobile coupling carriage and a guide therefor adapted to support the ship's coupling connection on a vertical axis at the uppermost part of the mooring apparatus, means of support therefor permitting rotation of the ship completely around the mooring carriage, and rail connections for said carriage extending laterally and downward to securely hold the ship against horizontal strain without change of coupling.

11. A mooring mast for airships comprising an extended tower, a substantially vertical guide on one side of said tower, a mobile coupling carriage engaging with horizontal strain-resisting members with the guide, a top section of said guide articulated to the main guide portion and having near its top shock-absorbing connections with portions of the tower on opposite side from the guide.

12. A mooring tower for airships comprising a non-laterally guyed main tower section, a turret top, a mobile coupling for the ship's connection, a guide for said coupling rotatable about a portion of the tower and rotatable with an upper portion of the tower, and an apex extension of said guide adapted to carry the mobile coupling to a substantially horizontal position above the centre of the tower.

13. A mooring mast for airships comprising a fixed base, a main section of tower rotatable within said base, a fixed guide on one side of said tower and mobile ship's nose coupling carriage engaging said guide and movable from the uppermost position of ship engagement substantially in the axis of the mast to a lowered position of ship engagement with the ground.

14. A ship's mooring mast comprising a mobile ship's mooring coupling carriage having means for engagement near the apex of the mast to resist lateral deflection of the car-

riage coupling, and means at a lower point to resist horizontal strain of said coupling carriage in a direction radial to the axis of the mast when the carriage is released from the lateral holding-means at the top.

15. An airship mooring tower comprising a sheathed structure having a generally stream-line horizontal cross-section, a ship's nose coupling rail extending vertically on one side substantially in the plane of the major axis of the tower section.

16. An airship mooring tower as set forth in claim 15, having a guide rail for a ship's nose coupling in a reentrant vertical surface on the leeside of the stream-line form when the mast is turned with the swing of the ship.

17. An airship mooring tower as set forth in claim 15, having a vertical elevator structure embodied at a maximum distance from the tower axis and adjacent the windward apex of the stream-line sheathing.

18. An airship mooring mast having a coupling carriage guide extending in a vertical plane on one side of the axis, and elevator structural supports embodied with the mast on the opposite side from the coupling carriage guide.

19. In a mooring mast for airships, a ship coupling carriage and a supporting guide therefor extending from the top and in the axis of the mast, curving laterally downward to a substantially vertical position along one side of the mast, an upper portion of said guide adapted to yield to strains on the carriage in the topmost position including lateral resilient members normally holding said topmost section of the guide in a position for registration and movement of the coupling carriage from the top section to the substantially vertical section.

20. A coupling carriage for mooring masts, comprising a frame with means for engagement and movement along guide rails on the mast, a housing pivotally-supported in said frame, and a coupling-pot rotatably supported in said housing.

21. A coupling carriage as set forth in claim 20, having means to lock the housing against oscillation in the frame.

22. A coupling carriage as set forth in claim 20, having means to lock the coupling-pot against rotation in the housing.

23. In an airship mooring mast, a ship's coupling engaging cone movable up-and-down the mast side on a guide stationary with relation to the mast axis, means contiguous with the apex of said cone adapted for the

passage of mooring cable and free from any fixed part of the mast, whereby after locking the ship's coupling in the cone a disconnection or slack in the mooring cable permits the free movement of the mooring coupling on the mast with the ship's coupling locked in the cone.

24. A mooring mast for airships comprising a sheet metal tower having a support at its base, airship nose-coupling gear at its top, means of support for the mooring gear transmitting ship strains to the sheet metal shell of the tower and haul-in gear extending down the interior and completely enclosed and protected by the tower sheathing.

25. An airship mooring mast comprising a round sheet metal enclosing and strain-resisting shell having an elevator on the interior of said shell and a ship mooring gear supported on the top of said shell by means transmitting horizontal strains on the mooring gear to and to be resisted solely by the shell of the tower.

26. An airship mooring mast comprising a mooring coupling-gear at the top, supports therefor extending downwardly and outwardly to the periphery of a hollow tower, a hollow tower extending downward to a base support and having a strain-resisting shell to resist ship strains on the mooring gear without outside guys for said tower.

27. An airship mooring mast consisting of a round sheet metal tower and having a base to support the same without lateral guys on said tower, mooring gear at the top of the mast with means permitting articulation of a mooring gear coupling directly above and without overhanging laterally from the axis beyond the radius of the tower.

28. An airship mooring mast comprising a sheet metal tower, a base support therefor, an elevator completely enclosed and movable up and down the inside of said tower, haul-in and mooring and supply apparatus completely enclosed extending through said tower to the top and cooperating with mooring gear, and means for controlling articulation of the mooring gear at the top of the tower without overhanging the lateral dimensions of the tower, whereby strains on the mooring gear are transmitted to the outer sheathing of the tower for the entire lateral resistance of said strains by-the-mast.

In testimony whereof, I have signed my name to this application this 18th day of August, 1925.

HERBERT V. THADEN.
